(57) **CLAIM**

The ornamental design for a nut holder, as shown and described.

DESCRIPTION

1. Nut holder

1.1: Perspective

1.2: Top

1.3: Left

1.4: Front

1.5: Right

1.6: Bottom

1.7: Perspective

Design 1 relates to the outer appearance of a nut holder with a bottom plate and side walls for holding a nut that is characterized by a set of opposing asymmetric hat portions extending from the side walls; Fig. 1.1-1.6 show the nut holder; Fig. 1.7 shows the nut holder with an optional example of a nut held therein. The broken lines depict environmental structure that forms no part of the claim.
